OVERHEAD-VALVE LUBRICATING AND
COOLING APPARATUS

Francis R. Good, United States Navy

Application November 4, 1946; Serial No. 707,547

4 Claims. (Cl. 123—90)

(Granted under the act of March 3, 1883, as
amended April 30, 1928; 370 O. G. 757)

1

This invention relates to apparatus for lubricating and cooling the exhaust and intake valve mechanism of valve-in-head engines such as internal combustion engines, compressors, and the like.

This application is a continuation in part of pending application Serial Number 687,545, filed August 1, 1946, and a continuation of application Serial Number 690,648, filed August 15, 1946, both now abandoned.

It is an object of this invention to efficiently flow a suitable lubricant from rocker arms to valve stems and associated apparatus in engines, compressors, and similar equipment, for the purpose of lubricating and cooling these members. The flow of lubricant over these parts serving to conduct away the heat while lubricating the moving parts, thus preventing excessive wear and permitting closer setting of the valves when cold, maintenance of proper clearance in the valves due to lower temperature operation, and consequent quiet and efficient operation.

It is a further object of this invention to provide an oil reservoir on a valve stem, in proximity to the rocker arm, whereby lubricant from the rocker arm may readily flow to the reservoir.

It is a still further object of this invention to provide simple and effective means for attaching an oil reservoir to a valve stem.

Another object of this invention is to provide means on a standard rocker arm adapted to conduct oil from the rocker arm bearing to a reservoir supported on the valve stem with which the rocker arm cooperates.

Another object of this invention is to provide means for retaining an oil conducting tube upon a rocker arm in such position that the tube will conduct oil to a reservoir supported on the valve stem with which the rocker arm cooperates.

Another object of this invention is to provide a rocker arm adapted to conduct oil to a reservoir supported on the valve stem with which the rocker arm cooperates.

Another object of the invention is to provide means for preventing the oil flowing over the end of the valve stem from entering the cylinder.

Further objects and advantages of this invention as well as its construction, arrangement and operation will be apparent from the following description and claims in connection with the accompanying drawings, in which the single figure shows an elevation view, partly in section, of a rocker arm with coating valve stem and associated parts.

In the figure a rocker arm 10, supported for

partial rotation on hollow oil filled shaft 11, is provided at one end with a tapped hole 12 wherein a suitable adjusting screw (not shown) is secured for contact with the push rod (not shown). In the upper portion of rocker arm 10 a suitable oilway 13 is provided so that, due to the motion of the rocker arm, lubricant from hollow shaft 11 will be forced outward through the upper hole 11a, which has restricted communication with the oilway 13 when the rocker arm is in the valve-closed, limit position shown in the drawing. Thence the lubricant flows thru tube 15 and if no additional parts were provided, would be sprayed over the valve stem contact end 14 and from there flow down the valve stem and adjacent apparatus for cooling and lubricating these parts. The apparatus thus far described constitutes a conventional method of lubricating the parts indicated.

20 In this invention a lubricant conducting tube 15, of copper or any other suitable material, is force fitted or otherwise secured at one end to the oilway 13, bent to roughly conform with the contour of rocker arm 10, and terminating near its contact end 14.

A spring wire clip 16 is bent from the front over and behind tube 15, toward the back of rocker arm 10, then bent downward and forward under the rocker arm, then upward and around the outer diameter of bearing hub 17 on the front side of the rocker arm, and then bent rearward under the adjusting screw end of the rocker arm, forming a simple and efficient clip to secure tube 15 in suitable operating position.

30 The circular cup 18, of aluminum or any suitable material adapted to quickly conduct the heat from the upper end of valve stem 26, is drilled to fit over the end of the valve stem and provided with one portion of a dovetail joint in its hub or base.

A portion 19, of the normal diameter of valve stem 26, is reduced to permit a cup retaining split collar or keeper 20, which contains the second portion of the dovetail joint, to be retained 45 in the slot formed by this reduced diametrical portion of the valve stem so that when the oil cup or reservoir 18 is placed in position over the larger diameter of the end of the valve stem, and the two halves of split collar 20 inserted in place, 50 these members are readily maintained in operating position by means of spring retaining collar 21, which is provided with a tapered bore coaxial with the tapered outer diameter of split collar 20, when upward pressure is placed on the collar 21 as by a spring 25.

Immediately below cup 18 is placed a ring or washer 22 of cork or other suitable lubrication sealing material, and between the spring retaining collar 21 and spring 25 is placed a skirt or washer 23 of aluminum or other suitable material having its outer diametrical portion projected downward to act as an apron and prevent lubricant overflowing from cup 18 from running down the valve stem 26 and finding its way into the cylinder. This apron is particularly desirable in connection with the intake valves, and especially so in diesel engines, where the suction from the cylinder may draw in any oil around the valve stem and cause excessive smoking at the exhaust. In an actual test where excessive smoking was present the use of the apron above described was found to substantially eliminate the smoke and thus increase the usefulness and efficiency of the apparatus.

The arrangement herein shown and described has been found by actual test to be considerably more efficient than the method used heretofore and concentrates the cooling medium at surfaces desired without undesired contact with surrounding parts and consequent inefficient use and loss of the lubricant.

Retaining a quantity of relatively cool lubricant in heat conducting cup 18 for a short period of time tends to more effectively transfer the heat from the valve stem 26 than would occur if the cooling medium was allowed to rapidly flow over these parts with insufficient time of contact for efficient heat transfer.

It will be understood that this invention may be made and utilized in any suitable shape, size, or arrangement, depending upon the work to be accomplished and that various modifications and changes may be made in this invention without departing from the spirit and scope thereof as set forth in the appended claims.

The invention described herein may be manufactured and used by or for the Government of the United States of America for governmental purposes without the payment of any royalties thereon or therefor.

What is claimed is:

1. A valve improvement kit of parts adapted to be installed upon the head of a valve stem in an overhead valve type of engine, said engine including, in addition to the valve stem having a circumferential groove near the top thereof, a collar having a tapered bore, a two-part, or split, tapered keeper embracing said stem at the groove and held within said collar bore, and a spring compressed beneath said collar, comprising: a split, tapered keeper adapted to replace the first mentioned keeper and characterized thereover by the provision of recesses in the inner surfaces of its two halves adjacent the valve stem; and a cup having an upwardly extending recess in the base thereof adapted to seat over the top of the valve stem, said cup having an outwardly extending flange portion on the base thereof around said recess adapted to lock into the recesses in said keeper.

2. A valve improvement kit of parts adapted to be installed upon the head of a valve stem in an overhead valve type of engine, said engine including, in addition to the valve stem having a circumferential groove near the top thereof, a collar having a tapered bore, a two-part, or split, tapered keeper embracing said stem at the groove and held within said collar bore, and a spring

5 compressed beneath said collar, comprising: a split, tapered keeper adapted to replace the first mentioned keeper and characterized thereover by the provision of an inwardly extending groove around the inner surface of the keeper adjacent the valve stem; and a cup having an upwardly extending recess in the base thereof adapted to seat over the top of the valve stem, said cup having on the base thereof a flange adapted to lock into the groove in said keeper.

3. A valve improvement kit of parts adapted to be installed upon the head of a valve stem in an overhead valve type of engine, said engine including, in addition to the valve stem having a circumferential groove near the top thereof, a collar having a tapered bore, a two-part, or split, tapered keeper embracing said stem at the groove and held within said collar bore, and a spring compressed beneath said collar, comprising: a split, tapered keeper adapted to replace the first mentioned keeper and characterized thereover by the provision of an inwardly extending, annular groove around the inner surface of the keeper adjacent the valve stem; a cup having a central bore thru the base thereof adapted to seat around the top of the valve stem, said cup having an outwardly extending annular flange on the base thereof around said recess adapted to lock into the groove in said keeper; and a washer adapted to be inserted around the upper edge of said second mentioned keeper immediately beneath said cup.

4. A valve improvement kit of parts adapted to be installed adjacent the head of a valve stem in an overhead valve type of engine, said engine including, in addition to the valve stem having a circumferential groove near the top thereof, a collar having a tapered bore, a two-part, or split, tapered keeper embracing said stem at the groove and held within said collar bore, and a spring compressed beneath said collar, and a rocker arm bearing against the top of the valve stem; comprising: a split, tapered keeper adapted to replace the first mentioned keeper and characterized thereover by the provision of an inwardly extending, annular, dovetail groove around the inner surface of the keeper adjacent the valve stem; a cup having a central bore thru the base thereof adapted to seat around the top of the valve stem, said cup having on the base thereof an outwardly extending annular dovetail joint around said recess adapted to lock into the dovetail groove in said keeper; a washer adapted to be inserted around the upper edge of said second mentioned keeper immediately beneath said cup; a skirt having an inwardly extending flange adapted to be held against the under side of said collar by the spring, a tube adapted to be secured to said rocker arm for conveying oil into said cup; and a spring wire adapted to clip over said rocker arm to hold said tube thereto.
